MEDICATED INSOLE

Joseph P. Leindorf, Pelham Manor, N. Y.

Application October 7, 1935, Serial No. 43,956

2 Claims. (Cl. 36—43)

This invention relates to new and useful improvements in medicated insoles for shoes, footwear, etc.

An object of this invention is to provide medicated insoles devised for the absorption, neutralization, deodorization of the sweat excreted from the wearer's feet, and insulating the insoles from the shoe insoles.

Another object of this invention is to provide insoles impregnated with a layer of suitable medicaments which will impart an agreeable fragrance to the feet and shoes of the wearer.

Another object of this invention is to provide embossed insoles having suitable plastic medicaments in the upper depressions and air pockets in the lower depressions for insulating the stockings of the wearer from the soles of the shoes.

Another object of this invention is to provide, as a new article of manufacture, sanitary absorbent and protective insoles which may be manufactured and distributed at a low cost consistent with discarding of a pair of such articles almost daily by any user.

With the above and other objects in view, the invention will be hereinafter more particularly described and shown in the accompanying drawing and pointed out in the claims which form part of this specification.

Reference will now be had to the drawing, wherein like numerals of reference designate corresponding parts throughout the several views, in which:

Figure 1 is a plan view of an insole embodying my invention.

Figure 2 is a sectional view, the section being taken as on line 2—2 in Figure 1, upon an enlarged scale and with depth dimensions exaggerated.

Figure 3 is a plan view of a modified insole having embossed depressions alternately disposed all over the upper and lower surfaces of the insole, the upper depressions being filled with plastic medicaments.

Figure 4 is a sectional view on an enlarged scale in the depth dimension of the insole shown in Figure 3, the section being taken as on line 4—4.

In the illustrated embodiment of the invention, the numeral 10 indicates an insole made of a single sheet of fibrous absorbent material such as thin blotter board. The major portion of the depth of the board is impregnated with plastic medicaments having antiseptic properties and serving to prevent putrefaction of the sweat or perspiratory matter excreted from the wearer's feet. This absorbent portion 11 absorbs and re-

tains the excess moisture from the foot of the wearer. The lower portion 12 of the insole is coated with a moisture repelling medium so as to insulate the shoe sole from the perspiration. When the insole is in use, the warm moisture from the foot is sufficient to slightly soften the plastic medicaments which soothe and heal the foot.

The lower side of the insole I prefer to treat with a paraffin and wax compound of equal proportions forming a moisture repelling medium. The insole is impregnated from the upper side with glycerin.

The constant pressure of the foot against the treated insole causes a portion of the glycerin to penetrate the stockings, thus bringing the skin in contact with some of the glycerin. The porous insole acts as a resorbent agent and absorbs the excessive perspiration. Glycerin is known to be helpful in cases of bromidrosis. The substances which give rise to the clinical symptoms of bromidrosis such as indol and skatol are the products of bacterial action. The addition of glycerin to the medium in which the indol producing bacteria are growing prevents the formation of this substance and in place of an alkaline medium the fermentation of the glycerin leads to the production of a marked acidity and so substitutes an acid for an alkaline medium. The glycerin prevents putrefaction of the sweat.

As shown in Figures 3 and 4, there has been provided a modified medicated insole 13 made of a single sheet of fibrous absorbent material such as thin blotter board and having embossed substantially square-shaped depressions 14 alternately disposed all over the upper surface and embossed substantially square-shaped depressions 15 alternately disposed all over the lower surface of the insole. The depressions 14 and 15 deform the sheet in a vertical direction so that it is of considerable depth. The upper depressions 14 have been filled with plastic medicaments 16 having antiseptic properties. The lower depressions or cavities form air pockets serving to insulate the insole from the shoe insole. The lower surface of the insole 13 is coated with a liquid substance which will not melt at the body temperature such as collodion 17.

It is to be noted that the air pockets 15 are separated units and that there is no communication between adjacent air pockets 15 or between said pockets and the upper surface of the insole.

Due to the weight of the person standing on the insole, the embossed and vertically distended paper gets pressed down and flattened out and causes the warmed medicaments to gradually rise

through the apertures in the stockings into direct contact with the feet of the user.

The invention provides a cheap and substantially highly medicated insole to be inserted between the stocking feet and the soles of the shoes for sanitary and protective purposes. While the insoles serve as a protection against outside dampness and cold, they are especially beneficial for persons who are subject to profuse foot perspiration. The absorbent body of the insole serves to absorb and retain the excess moisture from the foot which otherwise soils the sole of the shoe. The embossed insoles 13 also afford a cushioning effect and protection against irregularities in the normal interior surface of the shoe sole.

The preparations which I presently prefer for filling the upper surface of the embossed insoles 13 are as follows:

20 *First preparation*

	Ounces
Paraffin	3
White beeswax	3
25 Granulated camphor	1
Phenol crystals	1
Oil of pine	1
Boric acid powder	8

Melt the paraffin and wax in separate containers by heating on a water bath. Melt the phenol over a mild heat and stir in the camphor until dissolved. Add the phenol to the paraffin and wax. Also add the oil of pine and stir in the boric acid powder. Keep stirring and agitating till a thick smooth paste is formed. This preparation must be kept on a moderately heated water bath as excessive heat would rapidly evaporate the phenol, camphor and oil.

40 *Second preparation*

	Parts
Boric acid powder	15
Oil of eucalyptus	1

Mix the oil of eucalyptus with the boric acid powder.

The process of filling the depressions in the upper surface of the embossed insole 13 is as follows:

Lay the insole previously treated with the antiseptic flexible collodion on a smooth steel plate heated to about 135° F. (collodionized side down) and with the aid of a small trowel spread the heated paste till the depressions are partly filled. Spread the second preparation with a firm downward pressure and cover the partly filled depressions and form a smooth and unperforated level surface. Remove the insole from the hot plate and polish it with boric acid powder, using a

woolen pad, till the convexed parts are perceptible and giving the surface a two-tone effect (dark and light squares or whatever the embossed design may be). The heated plate is utilized for two purposes. The heat renders the first preparation plastic and pliant and causes the second preparation (boric acid powder) to unite with the first preparation causing the boric acid powder to set firm in a plastic state.

The paraffin and wax serve as a vehicle for the 10 boric acid powder and the volatilizing antiseptic oils and camphor. It is also used for the purpose of setting the foot on a plastic base where the toes and the heel make impressions and cavities which provide a comfortable resting place 15 for each individual digit of the foot. Wax being flexible, would be a preferable filling material. However, due to the fact that wax is viscous or sticky, the paraffin is added because being brittle, it imparts an element of rigidity.

20 It is to be noted that the boric powder is set sufficiently to remain united with the insole and still be in such plastic state as to be wiped into the stocking.

It is also to be noted that while I have shown 25 the insole 13 embossed with localized cavities impressed from opposite sides, that I may corrugate the flexible board with alternate ridges and valleys. Any thin, porous and flexible board yielding to impression and embossment may be 30 used for the insoles.

I claim:

1. An insole comprising a single sheet of flexible board impressed from opposite sides to form separated and localized cavities, the cavities in 35 one surface being alternately disposed with respect to the cavities in the opposite surface, the cavities in one surface being filled with plastic medicaments and said medicaments being entirely exposed all over the upper surface of said insole, the cavities in the opposite surface forming separated air pockets, said board being distended in a vertical direction and capable of being compressed when in use thus causing said plastic medicaments to be gradually raised above the 45 upper surface of said board.

2. An insole comprising a single sheet of flexible material impressed from opposite sides to form cavities, the cavities in one surface being filled with plastic medicaments and said medicaments being entirely exposed all over the upper surface of said insole, the cavities in the opposite surface forming separated air pockets, said insole being distended in a vertical direction and capable of being compressed when in use thus causing 50 said plastic medicaments to be raised above the upper surface of said sheet.

JOSEPH P. LEINDORF.
